UNITED STATES PATENT OFFICE

ERVIN W. McCULLOUGH, OF INDIANAPOLIS, INDIANA

GARBAGE REDUCER

Application filed July 23, 1923. Serial No. 658,403.

My invention described and claimed herein relates to a combination rendering tank for reducing garbage and the like.

The main object of my invention is to construct a combination rendering tank in which garbage and the like may be cooked and disintegrated, separated from its major water content, dried and then mechanically discharged in a disintegrated relatively dry state from said tank.

The chief feature of the invention consists of the dewatering or draining mechanism which permits successful and relatively rapid drainage of substantially the entire free water content of the tankage, whereby the de-watered tankage may thereafter, in the same tank, be dried (and retained in suitable form) for subsequent operation as claimed in the copending continuation-in-part application Serial No. 698,106, which otherwise would be impossible if the free water content was not substantially and entirely removed from tankage, if derived from garbage and the like.

Another feature of the invention and a direct result of the foregoing, consists in the equipment of the combination rendering tank having the dewatering device specified with an agitator and a door, whereby after the tankage has been dewatered and dried to the desired degree, said tankage is mechanically discharged through the door by the agitator, thus discharging the tank contents in a relatively short time.

Referring to the accompanying drawings, which are made a part hereof and on which similar reference characters indicate similar parts,

Figure 1 is an elevation, partly in section, of the cooking and drying tank,

Figure 2, a horizontal section on line 2—2 of Figure 1,

Figure 3, a detail of the door frame of the tank,

Figure 4, a plan of the door frame viewed from above,

Figure 5, a detail of the door,

Figure 6, a plan of the door, and

Figure 7, a detail of a part of the door in Figure 6.

In the drawings reference character 10 indicates a cylindrical shell forming the outer wall of a tank corresponding to the ordinary rendering tank. The ends of this shell are closed by a bottom plate 11 and a cover plate 12. The cover plate has a central opening surrounded by a cover frame 13 which in turn is closed by a cover 14 and is secured in closed position by a plurality of swing-bolts 15 pivotally mounted on the cover frame and engaging at their upper ends in radial slots in the cover, said bolts having nuts 16 for drawing the cover down on its seat.

The cover frame has projecting therefrom a vacuum pipe 17 and a blow-off line 18 though a single pipe may be substituted for the two if desired. The cover 14 may be provided with a vent pipe through which gas may escape during the cooking period or as here shown a vent pipe 19 may be mounted on the blow-off pipe. The vent pipe in this instance is connected to the blow-off pipe at opposite sides of a globe valve 20, and is itself provided with a globe valve 21, the blow-off pipe being also provided with a similar valve 22.

Within the body of the tank there is located a plate 23 parallel to the bottom plate 11, this plate being supported in any preferred manner as by means of staybolts 24 and I-beams 25. The plate has a central opening corresponding to the central opening in the plate 11 said opening receiving a hollow bearing 26 in which is journaled a shaft 27. The follower or gland 28 of an ordinary stuffing box is interposed between the shaft and the bearing said follower acting on packing interposed between it and a bushing 28'. The bearing has a shoulder interposed between the plates 11 and 23 and the parts are held tightly together by means of rivets 29 passing through the plates and the shoulder in a manner to prevent leakage of fluids between the parts. A set screw 30 passes through a flange on the follower 28 into said bearing for adjusting the follower.

A shell 31 of approximately half the length of the shell 10 is secured at its lower end to the plate 23 and at its upper end to the shell 10 in such a manner that the concentric

shells form a steam jacket by means of which the space inside the tank may be heated for cooking or in drying material in the tank. This space communicates with the space between the parallel bottom plates and a series of cooking pipes 32 is provided at spaced intervals about the boiler to admit steam into the boiler at various points for the purpose indicated. Other heating media such as hot water may be used if preferred. A drain pipe is shown at 33 for removing material from the lower part of the tank, the drain pipe being preferably opposite the door 34 which forms the exit from the tank. A pipe 33' admits steam to the jacket and a pipe 34' serves as an exhaust pipe. A plurality of outlet pipes 35 are arranged at regularly spaced intervals diagonally down the side of the tank, these pipes extending into the inner chamber and being provided with valves for opening and closing the passages. The diagonally arranged pipes provide drain openings by means of which melted fats and other liquids may be drained off successively at various levels in the tank.

The door 34 is shown in detail in Figures 5 and 6 and consists of an outer plate 36 with perforated rearward extensions 37 by means of which the door is hinged to arms 30 on a frame 38 secured to the front of the tank in any convenient manner. It is here shown as having edges projecting between the concentric sheets where they may be secured by rivets or in any other desirable manner. The door has a series of notches 39 arranged about its outer edges adapted to receive swing-bolts 40 pivotally mounted in ears 41 on the door frame. The door, near its outer edge, bears against an out-standing flange 42 on the door frame and inside said flange is directed inward toward the boiler as shown in Figure 2 so that its inner face is substantially continuous with the inner face of shell 10. Projections 43 on the door support a perforated plate 44 (Fig. 2) which in a preferred form of the invention has a limited number of large openings about one inch in diameter and a larger number of holes of smaller size, ($\frac{3}{8}$ inch have been found satisfactory in use). The plate 44 is arranged concentrically with the inner face of the shell 31 and is substantially continuous therewith. The inner faces of the shell and the door and the inner face 45 of the door frame coact to form a substantially uniform cylinder. The outstanding flange on the door frame is perforated at 46 and an enlarged lug 47 at this point is internally threaded to receive the end of a pipe 48 by means of which liquids may be let off substantially at the bottom level of the tank. Plate 44, door 34 and the door frame flanges 42 form a discharge chamber.

The shaft 27 has secured to it at its upper end within the tank a pair of arms 49 located close to the floor of the tank and having in

their undersides at 50 longitudinal grooves terminating at the outer ends of the arms which grooves facilitate draining of the tank. The arms extend nearly to the shell 31 and each of them carries on its upper face a pair of plates or standards 51. These plates are thickest at the lower rear corner and taper therefrom upward and forward, the narrower edge being the forward edge when the agitator formed by said arms is turned to agitate material in the tank.

Shaft 27 may be driven in any convenient manner. As one convenient means I have here shown a ring gear 52 meshing with a pinion 53 on a shaft having at its other end a gear 54 driven by a pinion 55 on the shaft of an electric motor 56.

The method or process of operation is as follows: The agitator is first turned so as to bring the end of one of the arms directly opposite the pipe 33 and the other end opposite the perforated plate 44 on the discharge door. It is found that this position gives very much better results than any other in the way of draining the liquid out of the tank, and in fact really is important to satisfactory operation. It is preferable first to fill the bottom of the tank with water sufficient to start the cooking. A charge of garbage is then placed in the tank through the charging opening in the top, the amount varying according to the capacity of the tank; all outlets in the tank are tightly closed excepting the small vent pipe in the top which is left open for the escape of gases; live steam is admitted from several points into the inner chamber in direct contact with the garbage for a sufficient length of time to cook the garbage thoroughly, the time required being readily determined by the operator after cooking a few charges, the steam pressure in the tank being kept at approximately 80 pounds for the best results. The pressure, however, may vary according to conditions and the quality of the garbage.

After the charge is thoroughly cooked it is allowed to cool sufficiently to cause a cessation of ebullition and to allow the greases to rise to the top of the mass. This operation may be hastened by maintaining a vacuum in the tank which may be done by any mechanical means suitable for that purpose. After proper cooling has been accomplished and the grease has risen to the top of the charge the free grease is removed by either skimming or by floating it off through the series of drain pipes 35 in the side of the tank. By using these openings progressively from the top downward the grease is first drawn off and then the free garbage liquor as the solids gradually settle in the tank. The remaining liquor is drawn off at the bottom of the tank through the opening 33 and through the perforated plate 44 on the inner face of the discharge door and out through the discharge

drain pipe 48, at the side of the door frame 38. After the liquor ceases to flow freely by gravity the drainage may be hastened and the remaining liquor forced out by the application of steam pressure to the top of the charge, the steam being admitted slowly allowing the pressure to build up gradually. The steam should not be used as long as satisfactory results are being obtained by gravity flow.

With the cooking and draining operations complete all outlet openings of the tank are again closed and steam is turned into the jacket between the shells for drying the residue. A vacuum of desirable degree is then established in the inner chamber of the tank, the agitator 49 started and the operation continued until the drying is completed. The vacuum to be applied varies with the nature of the material being treated but any vacuum that can be produced by mechanical means will suffice. During the drying process the organic material most desired is disintegrated, shredded and torn into small particles by the action of the agitator while the foreign matter such as metals, glass, crockery, wood, rags, strings and the like are left in substantially the same condition and size as when placed in the tank, thus preparing the treated garbage which now becomes dried tankage for the next step in the process. The vacuum is now broken, the discharge door 34 opened and the agitator is rotated to assist in the discharge of the tankage. The tankage is then allowed to cool which may be hastened by spreading it out so as to expose it to the air.

It is to be understood also that the device is not limited in use to garbage reduction, but may be applied to other uses for which it is or may be found suited, and that, therefore, throughout the specification and claims the term "garbage" is to be interpreted as meaning any substance for the reduction and separation of which the invention may be adapted.

Having thus fully described my said invention, what I claim as new and desire to secure by Letters Patent, is:

1. In a tank for cooking and draining organic material such as garbage, or the like, the combination of a side wall having an opening therein adjacent the tank bottom, a single metallic and perforated plate substantially conforming to the side wall conformation, a door for said opening in spaced relation to the plate, passage forming means communicating with said opening and forming a chamber with the door and plate and having restricted communication with the tank interior through said plate when the latter substantially completes the side wall, and means other than opening the door for draining said chamber, said plate including a plurality of dissimilar sized openings which ex-

tend entirely through the plate and provide the aforesaid restricted communication, said openings including a relatively large number of small openings and a smaller number of relatively larger openings.

2. A device as defined by claim 1 characterized by the larger holes being substantially 1" in diameter and the smaller being substantially $\frac{3}{8}$ " in diameter.

In witness whereof, I have hereunto set my hand at Indianapolis, Indiana, this 20th day of July, A. D. nineteen hundred and twenty-three.

ERVIN W. McCULLOUGH.
